Wesley Glenn
ATTORNEY

UNITED STATES PATENT OFFICE.

CHRISTIAN AALBORG, OF WILKINSBURG, PENNSYLVANIA, ASSIGNOR TO WESTINGHOUSE ELECTRIC & MANUFACTURING COMPANY, A CORPORATION OF PENNSYLVANIA.

DISK TYPE INSULATOR.

Application filed November 13, 1919. Serial No. 337,631.

To all whom it may concern:

Be it known that I, CHRISTIAN AALBORG, a citizen of the United States, and a resident of Wilkinsburg, in the county of Allegheny and State of Pennsylvania, have invented a new and useful Improvement in Disk Type Insulators, of which the following is a specification.

My invention relates to insulators and particularly to strain insulators of the disk type.

One object of my invention is to provide a device of the above indicated character that shall be simple and durable in construction, economical to manufacture, easy to assemble and effective in operation.

Another object of my invention is to provide a strain insulator that shall be so formed as to provide a relatively great surface-creepage distance.

Another object of my invention is to provide a strain insulator of the disk type that shall permit the use of rigid metal terminal members in co-operation therewith, thereby eliminating some of the difficulties attending the use of flexible cables, such as providing enlarged heads, splices and other means for securing the cables together and to adjacent fastening means.

In practicing my invention, I provide an integral body member, preferably of porcelain, although other insulating material may be used, having a main or central, substantially cylindrical body portion of relatively small diameter and a plurality of discoidal petticoat portions. The body member is so provided with intercepting substantially right-angularly related openings as to permit a plurality of rigid metal members, such as bolts, to be easily placed in the openings and secured to each other. By the specific form and arrangement of the body and petticoat portions, the insulator is provided with a very effective amount of creep-

age surface, its manufacture and assembly are facilitated and more convenient handling, packing and shipping thereof is permitted than with insulators of irregular or odd shapes. The use of rigid metal members permits the employment of standard fastening devices, such as nuts and bolts, therewith, and renders less difficult the placing of the insulators close together, thus permitting a greater number of insulators

to be strung in a given distance and increasing the insulating value of the string. 55

Figure 1, of the accompanying drawings, is a side view, partially in elevation and partially in section, of an insulator embodying my invention; Fig. 2 is an end view of 60 the device shown in Fig. 1, and Figs. 3 and 4 are views, similar to Figs. 1 and 2, respectively, of a modified form of insulator embodying my invention.

An insulator 1, preferably of porcelain, 65 comprises a substantially cylindrical body portion 2 and a plurality of discoidal petticoat portions 3. Pairs of transverse openings 4 and 5 are spaced laterally with respect to each other and along the longitudinal axis of the insulator, the openings 4 being intercepted, at one side, by longitudinal openings 6 that extend to an end surface 7 of the body portion 2, and the openings 5 being intercepted, at one side, by 75 longitudinal openings 8 that extend to the opposite end surface 9 of the body portion 2. The openings 4, 5, 6 and 8 are preferably formed in the body portion during the molding or other process of constructing the 80 insulator.

Transverse members 10 and 11, preferably conforming closely in size and shape to the openings 4 and 5, respectively, are provided with interiorly threaded side openings 12 85 that are adapted to register with the openings 6 and 8, respectively, to receive terminal members or rods 13 and 14 that extend into the body portion from opposite ends thereof.

The construction shown in Figs. 1 and 2 90 provides a rectangular framework inside the body portion by which longitudinal stresses transmitted between the opposite end terminal members are effectively and widely distributed. That is, there are substantially 95 two sets of interlinked metal structures by which the total force is divided to impose smaller fracturing stresses at different parts of the body member.

In Figs. 3 and 4, instead of pairs of the 100 transverse members 10 and 11, there is only one of each arranged at right angles to the other, the construction, in this form, being otherwise substantially the same as in Figs. 1 and 2. 105

In both forms, but as shown clearly in Fig. 3, the transverse members 10 and 11 are preferably constructed shorter than the

transverse openings through the body portion which they occupy, and the ends of the openings are filled with bodies 15 of cement or other suitable insulating material that 5 may be smoothed off to conform to the surface of the body portion.

While I have shown and described particular forms of my invention, changes may be effected therein without departing from 10 the spirit and scope thereof, as set forth in the accompanying claims.

I claim as my invention:

1. An insulator comprising a cylindrical body member of refractory material having 15 a plurality of integral annular petticoats forming a plurality of annular channels therebetween and a pair of diametrically-related longitudinal recesses in, and surrounded by, said body and extending from 20 each end surface of the body member to an inner position laterally opposite one of said channels, the diameters on which the recesses of said pairs are disposed being at right angles to each other, said member also 25 having lateral openings to the exterior of the body member each intercepting the inner ends of one of said pairs of longitudinal recesses and extending between opposite points in one of said channels, holding members disposed in the lateral openings and 30 terminal members in the longitudinal openings secured at the inner ends thereof to said lateral holding members, said holding and terminal members being placed in operative 35 position by insertion from the exterior of the insulating body in the direction of their longitudinal axes.

2. An insulator comprising an insulating body member having longitudinally-displaced and substantially right-angularly-related transverse openings therein and longitudinal openings extending from each 40 of said transverse openings to the end of the body member beyond the other transverse opening, holding members disposed in said transverse openings, and terminal members disposed in said longitudinal openings and held in position by said holding members, said holding and terminal members being placed in operative 45 position by insertion from the exterior of the insulating body in the direction of their longitudinal axes.

3. An insulator comprising a preformed insulating body member having longitudinally-displaced and substantially right-angularly-related transverse openings communicating with the outer surface thereof and longitudinal openings extending from each of said transverse openings to the end 55 of the body member beyond the other transverse opening, holding members in said transverse openings, and terminal members in said longitudinal openings and held in position by said holding members, said holding and terminal members being placed in operative position by insertion from the exterior of the insulating body in the direction 60 of their longitudinal axes.

4. An insulator comprising a preformed insulating body member having longitudinally-displaced and substantially right-angularly-related transverse openings communicating with the outer surface thereof and longitudinal openings extending from each of said transverse openings to the end 65 of the body member beyond the other transverse openings, metal holding members of less length than the diameter of the body member inserted in said transverse openings beyond the surface of the body member, metal terminal members inserted in said longitudinal openings and held in position by said holding members, and bodies of insulating material disposed in said transverse 70 openings between the holding members and the surface of the body member.

5. The combination with an insulator comprising a single integral insulating body member having preformed intercepting lateral and longitudinal elongated openings each entirely circumferentially surrounded by the material, and accessible from the exterior of the body member, an elongated holding member for insertion along its longitudinal axis from the exterior of the insulator into said lateral opening, and an elongated terminal member for similar insertion from the exterior of the insulator into said longitudinal opening to co-operate 75 with said holding member.

In testimony whereof, I have hereunto subscribed my name this 30th day of Oct., 1919.

CHRISTIAN AALBORG.
